W. T. BRYANT,
TREATMENT OF PETROLEUM,
APPLICATION FILED NOV. 16, 1917.

1,403,145.

Patented Jan. 10, 1922.

UNITED STATES PATENT OFFICE.

WILLIAM T. BRYANT, OF SHREVEPORT, LOUISIANA, ASSIGNOR OF ONE-HALF TO
EARNEST R. RATCLIFFE, OF SHREVEPORT, LOUISIANA.

TREATMENT OF PETROLEUM.

1,403,145.

Specification of Letters Patent. Patented Jan. 10, 1922.

Application filed November 16, 1917. Serial No. 202,385.

To all whom it may concern:

Be it known that I, WILLIAM T. BRYANT, a citizen of the United States, residing at Shreveport, in the parish of Caddo, and 5 State of Louisiana, have invented certain new and useful Improvements in the Treatment of Petroleum, of which the following is a specification.

This invention relates to the treatment 10 of mineral oils and particularly to the conversion of such oils into hydrocarbons of lower boiling-points.

More particularly, the invention relates to the treatment of hydrocarbons containing 15 relatively large proportions of oils of the kerosene grade, for the purpose of recovering large amounts of lower-boiling hydrocarbons, notably those of the motor-fuel or gasoline type.

20 An object of the invention is to provide a practical and economical process which will yield an increased quantity of such low-boiling products.

Other objects and advantages will appear 25 as the description proceeds.

Briefly, the process comprises vaporizing the oil under pressure at a temperature which would be usually high enough to crack the oil but under such conditions that 30 no substantial cracking actually occurs, introducing pressure-steam in numerous jets along the bottom of the still to agitate the oil and otherwise stirring the oil so that by the combination of the two vigorous agitation is effected and formation and deposition of carbon is prevented, then passing 35 the vapors rapidly through a cracking-retort under substantially the same pressure as that employed in the vaporizing still, thereafter relieving the pressure and allowing 40 the entrained carbon to become deposited and finally condensing the condensable vapors. In case crude-oil is the starting material, the vaporizing of the oil through the gasoline-cut takes place under 45 substantially atmospheric pressure and the vapors are led directly to the condenser. When the gasoline-content is exhausted, the passage from the still to the condenser is 50 closed and the vapors are caused to pass through the cracking-zone, pressure being thereupon applied in both the still and the cracking-retort.

The apparatus comprises briefly a still 55 and a connected separate cracking-retort,

means for closing the connection between the still and retort and means for directly connecting the still with the condenser when the passage between the still and retort is closed, means for heating the vaporizing still to a relatively high temperature, means for vigorously agitating the oil in the still, means for applying pressure to the vapors in the still and retort, means for relieving the pressure upon the vapors 60 after they leave the retort and means for condensing the condensable vapors.

The invention will be better understood by reference to the accompanying drawing, in which one form of operating-plant is 70 shown, somewhat diagrammatically, partly in side-elevation and partly in section.

In the drawing, the numeral 1 indicates a still which may be of ordinary cylindrical form, supplied with oil by a pipe 2 which 75 passes preferably through the fire-box and flue of a suitable furnace 3 intended to heat the still 1. Oil is fed to the pipe 2 under a suitable head through a pipe 4 equipped with a valve 5. The still is preferably inclined slightly and the oil-supply pipe 2 is connected to the still at its lowermost point so that the contents can also be withdrawn through the pipe 2. For this purpose, a suitable drain-pipe 6 having a 80 valve 7 is connected to the outer end of pipe 2, so that by closing valve 5 and opening valve 7 the still 1 can be emptied.

The still 1 is equipped with a pressure-gauge 8, a safety-valve 9 and a pyrometer 90 or other suitable temperature-measuring device 10. The dome 11 has a pipe-connection 12 for conveying the vapors from the still. Near the bottom of the still and extending approximately the length thereof, 95 there is a metal agitator 13, conveniently of the cross-paddle type, fixed upon a shaft 14 mounted for rotation in bearings 15 in the still-ends. One end of the shaft 14 extends beyond the still and has thereon a 100 sprocket-wheel 16 which receives motion through an endless chain 17 from a sprocket-wheel 18 driven by an electric or other motor 19. Other means than that described may of course be employed for effecting rotation of the agitator 13. Close to the center of the bottom of the still 1, preferably between the latter and the agitator 13 and substantially co-extensive therewith, there is 105 a steam-pipe 20 having numerous perfora-

110

tions 21 along its lower side opposite the still-bottom. Steam under pressure is supplied to this pipe from any suitable source by a valved pipe 22. A second perforated 5 pipe 23 is connected to the pipe 22. This pipe 23 lies close to and follows the general contour of the top of the still and its dome and its perforations are upwardly directed, so that the steam impacts against the interior 10 of the still.

By means of a pipe 24 the vapors are conveyed from dome 11 and pipe 12 to a retort-coil 25 wherein the vapors are cracked. The retort is preferably of the type shown and 15 described in my copending application, Serial Number 202,384, filed Nov. 16, 1917. It is mounted in a furnace 26 heated by a burner 27 or other suitable means. The other end of the retort is connected to a 20 pressure-equalizer or reservoir 28 which in turn is connected through a pressure and velocity-regulating valve 29 to a pressure-relieving chamber or pipe 30 of considerably 25 greater cross-section than the retort-pipe. The pipe or chamber 30 connects with a suitable condenser 31. The pressure-equalizing drum 28 is provided with a suitable 30 pressure-indicator 32 and a clean-out opening and draw-off 33. The pipe 24 is provided with a valve 34 and a valved steam-supply pipe 35 may supply steam, preferably 35 superheated, to the vapors in the pipe 24.

A pipe 36 having a valve 37 connects the pipe 24 in front of the valve 34 directly with 40 the condenser, so that if valve 34 is closed and valve 37 is opened the vapors generated in the still will be carried to the condenser without having to pass through the retort 25.

Each section of the retort-coil 25 is, as described in my aforementioned application, 45 provided with an internal heating element 38, so that the heat of the tubes is conducted to the interior of the vapor-stream and one or several or all of the sections of the retort 50 may be provided with pyrometers or other suitable heat-measuring devices 39.

In operating with middle-distillates or oil from which the gasoline content has been removed, the valve 37 is closed and valve 34 55 is opened. Oil is run into the still 1 through pipes 4 and 2 until the still is approximately two-thirds full and the still is heated to the vaporizing-point of the lowest-boiling fractions, say 700° F. During the heating-up 60 steam is admitted to the pipes 22 and 23 under considerable pressure and the agitator is set in action. The vapors generated in the still together with steam pass through pipes 12 and 24 to the retort 25. The latter 65 has in the meantime been heated up to say 850° F., a little steam being allowed to flow through the retort-coil 25 meanwhile to protect the pipes and prevent burning. The temperature of the still is gradually increased until its contents attains a tempera-

ture of from 800° F. to 850° F. The temperature of the retort may also be gradually raised until the vapors therein reach a temperature of 1000° F. or more. The final temperature in the retort may, with care, 70 be increased to approximately 1200° F., but temperatures above this point are neither necessary nor advisable. If desired, and it is usually preferable, supplemental steam may be admitted to the stream of vapors 75 through pipe 35. As the vaporizing temperature is increased, the valve 29 is closed more and more so that the pressure in the system, including both the still 1 and the retort-coil 25 is increased as the vaporizing and cracking temperatures are raised. The pressure may be increased in increments of, say, twenty pounds per square inch after a pressure of forty pounds is applied, until the pressure reaches the desired maximum. 80 With a temperature of 800° F. in the vaporizing-still and a temperature of about 1000° F. in the retort, this maximum pressure may be about eighty pounds per square inch. The pressure may run as high as one hundred 85 pounds per square inch, or even higher, but such high pressures have not been found necessary.

During this high-temperature vaporization no substantial amount of decomposition 90 takes place in the still 1. This is due partly to the pressure in the still and partly to the combination of the steam-jets acting against the still which also causes local agitation of the oil and the vigorous agitation produced by the rotation of the agitator 13. By this combined arrangement, it is almost impossible for a particle of oil to remain in contact with the surface of the still long enough to become cracked. The particles 95 get just heat enough to vaporize them and the vapors are carried immediately to the space above the oil-level, there mixed with steam and are then swept on through the retort 25. Substantially no carbon is 100 formed in the vaporizing-still, therefore, and even if a small amount was produced, it would be harmless as the steam-jets and the agitator would in their combined action 105 maintain the particles of carbon in suspension and away from the metal of the still. It has been found that the combination of the two is essential. If the agitator is omitted, the steam-jets would not be sufficient to agitate the heavy oil and especially the residuum occurring toward the latter part of 110 the distillation. The paddle-wheel is not alone sufficient to prevent the formation of the gummy film on the still-bottom. This gummy residue is much like glue in its nature and if allowed to settle on the bottom 115 would soon form an incrustation which would cause buckling and burning-out of the still. If both means are not employed, the heating-effect would in a short time become 120

so diminished that it is impossible to distill off more than one-third of the still contents if pressure is present. Any attempt to distill a further amount would cause buckling and incrustation. On the contrary, if the combination of the steam-jets and paddle-agitator is used, it becomes quite possible to distill off as much as seventy-five per cent of the oil in the still. Enough oil is then left to amply protect the bottom of the still.

If the starting-material is crude-oil containing gasoline and other low-boiling hydrocarbons, the oil may be run into the still while the latter is cold. The oil and still can then be gradually heated up together. The distilling off of the fractions boiling below, say, 400° F. takes place under atmospheric pressure and the vapors are conveyed directly to the condenser 31 through pipe 36, valve 37 being now open, and valve 34 closed. If the furnace 26 is being heated, a small quantity of steam may be allowed to flow into and through the coil 25 from steam-inlet pipe 35, to prevent burning-out of the pipes of the retort. During this simple, low-temperature distillation just enough steam is admitted through the perforated pipe 20 to cause a little agitation. It is not necessary then to operate the mechanical agitator 13. As the boiling-point of the oil becomes higher, the temperature is raised and the steam-pressure is increased. When the gasoline-cut is completed, valve 37 is closed, valve 34 controlling the passage to the retort is opened and the temperature of the still is gradually increased. Furnace 26 has been heated up meanwhile and the vapors passing through the retort 25 are cracked in the manner hereinbefore described. Valve 29 is closed little by little to effect the proper working-pressure throughout the system, the final pressure being preferably about eighty pounds per square inch when the temperature of the oil in the still reaches, say, 800° F. As soon as the pressure is applied and the vaporizing temperature raised above that of the gasoline-cut, the agitator 13 is set in motion and the flow of steam through the perforated pipes 20, 23, is increased. As in the treatment of the middle-distillates, additional steam may be admitted to the retort-coil, with the oil vapors, through pipe 35. The conditions of operation of this cracking process are precisely those set forth for the treatment of middle-distillates, so that no further description thereof is thought necessary.

By the use of the method and apparatus herein-described, the temperature at which vaporization takes place during the cracking-step can be maintained very high so that the oil is readily vaporized, without incidental decomposition of the oil in the still and the formation of troublesome carbon.

Such decomposition does not take place until the vapors reach the retort 25 and any carbon therein formed is swept along by the current of vapors beyond the regulating-valve 29 and into the enlarged pressure-relieving pipe or chamber 30 where it is deposited and from which it can be readily removed.

I claim:—

1. The process of converting oils into lower-boiling hydrocarbons, which consists in heating in a still a relatively large quantity of oil, to vaporize it, under pressure, at a cracking temperature, introducing steam under pressure into and vigorously agitating the oil to prevent any substantial cracking thereof, then passing the vapors through a cracking-zone at a velocity sufficient to prevent substantial deposition of carbon and under substantially the same pressure as that employed in the vaporizing-step, then releasing the pressure upon the cracked vapors thereby causing the entrained carbon to become deposited and finally condensing the condensable vapors.

2. The process of converting oils into lower-boiling hydrocarbons, which consists in heating in a still a relatively large quantity of oil, to vaporize it, under pressure, at a cracking temperature, introducing steam under pressure into and vigorously agitating the oil to prevent any substantial cracking thereof, introducing steam into the vapors and passing the vapors thus mixed with steam through a cracking-zone at a velocity sufficient to prevent substantial deposition of carbon and under substantially the same pressure as that employed in the vaporizing-step, then releasing the pressure upon the cracked vapors thereby causing the entrained carbon to become deposited and finally condensing the condensable vapors.

3. The process of converting oils into lower-boiling hydrocarbons, which consists in heating in a still a relatively large quantity of oil, to vaporize it, under a pressure of from 40 to 100 pounds per square inch and at a cracking temperature of 700° F. to 850° F., introducing steam under pressure into and vigorously agitating the oil to prevent any substantial cracking thereof, then passing the vapors through a cracking-zone maintained at a temperature of from 850° F. to 1200° F., at a velocity sufficient to prevent substantial deposition of carbon and under substantially the same pressure as that employed in the vaporizing-step, then releasing the pressure upon the cracked vapors thereby causing the entrained carbon to become deposited and finally condensing the condensable vapors.

In testimony whereof, I affix my signature.

WILLIAM T. BRYANT.
